UNITED STATES PATENT OFFICE.

WILLIAM B. WAIT, OF NEW YORK, N. Y.

SHEET-GAGE.

1,090,666.

Specification of Letters Patent. Patented Mar. 17, 1914.

Application filed August 14, 1913. Serial No. 784,782.

To all whom it may concern:

Be it known that I, WILLIAM B. WAIT, a citizen of the United States, residing at New York, in the county of New York and State 5 of New York, have invented new and useful Improvements in Sheet-Gages, of which the following is a specification.

This invention relates to a sheet gage which is essentially adapted to be applied to 10 an embossing machine of the kind described in my U. S. Patent application Ser. No. 732,079 filed December 20th 1912.

The present invention includes means cooperating with one of the embossing cylinders whereby the head of the sheet when it is slid along the feed board toward the circumference of the cylinder and before it is 15 grasped by the gripper, is held between fingers mounted to oscillate at predetermined 20 times.

By means of this invention the fingers are actuated to release the head of the sheet simultaneously when the grippers grasp the sheet to carry it with the cylinder. These 25 fingers guide and gage the sheet to give perfect alinement relative to the embossing cylinders, and the succeeding sheet can be positioned between the fingers before the tail of the first sheet has passed under the fingers. By this method the machine can be 30 rotated at high speed and a sheet embossed without skipping any of the revolutions of the cylinders.

Further details of the invention are more 35 fully described in the following specification and claims, and illustrated in the accompanying drawings in which:

Figure 1 is a side elevation of an embossing press embodying this invention. Fig. 2 40 is a front elevation the feed board and cylinder adjusting devices having been removed.

In these drawings is shown an embossing machine including side frames *a* between 45 which are mounted a pair of cylinders *b*. These cylinders carry plates *c* for embossing a sheet of paper *d* on both sides. One of the cylinders is journaled in sliding boxes *e* having adjusting devices *f* for moving the 50 cylinder to or from the opposite cylinder. One of the cylinders carries a gripper *g* of well known construction. A feed board *h* serves to support the sheets of paper before 55 being embossed. The cylinders are rotated in the proper direction by means of gears *i*

driven by a pulley *j* with belt connection to a motor.

The gaging devices for guiding the sheet from the feed board consist of a cam *k* secured to the shaft of one of the cylinders. 60 This cam is timed to operate the gaging devices at every revolution of the cylinders. The gaging connections include a rock shaft *m* extending across the top of the machine, and journaled in standards *n* secured to the 65 frame. This shaft is provided with collars *o* two or more, clamped to the shaft by means of thumb screws *p* threaded in the collars. Each collar carries a slotted sheet stop or finger *q* having a thumb screw *r* for mounting 70 the finger on a collar. This sheet stop can be adjusted vertically relative to the cylinder by actuating a thumb screw *s* in engagement with the upper angular portion of the finger and threaded in the top of the 75 collar. A lever *t* is secured to the rock shaft and fulcrumed at *u* to an upright *v* movably connected by means of a pin and slot *z* to the frame. The other end of this lever is pivoted to a vertically arranged link *w* having 80 at its lower portion an anti-friction roller *x* normally in contact with the periphery of the cam. The link has its lower end slotted to engage a stud *y* extending from the frame. A spring *z* is adapted to hold the roller in 85 engagement with the cam.

The lower portion of the sheet stop has a hook portion or finger *g* bent at right angles to the vertical portion of the stop for supporting the head of the sheet. Above 90 this hook portion is fixed a springy metal member *h* having an upwardly curved portion. This device in combination with the hook portion of the stop constitutes fingers for holding the head of the sheet. 95

It will be seen that when the sheet is positioned between the two fingers it is supported on the hook member, while the upper springy member prevents upward movement of the sheet. In this arrangement the 100 edge of the sheet is stopped by the vertical portion of the stop, and thus gaged to be in a straight line with the cylinder. The gaging devices are operated when the anti-friction roller is in contact with the low 105 portion of the cam thus moving the link downward by means of the spring and rocking the lever *t* and the shaft. Through these connections the stop *g* is oscillated to move from under the head of the sheet which then 110

drops on to the cylinder in the path of the grippers and is thereby carried about the cylinder.

It should be understood that the cam imparts intermittent movement to the sheet stop, in other words when the anti-friction roller is in contact with the concentric portion of the cam, the stop remains stationary or in a position to hold the sheet. The concentric portion of the cam includes about three-quarters of its circumference and the eccentric portion the remainder so that the sheet stop will be in its stationary position for the succeeding sheet while the first sheet is being embossed by the cylinders. This arrangement gives more time in which to feed the sheets than when feed points are used.

I claim:

20 1. In a sheet gage the combination with a pair of embossing or printing cylinders, grippers carried by one of the cylinders, a rock shaft located over the gripper cylinder, an adjustable clamp mounted on the rock shaft, a sheet stop carried by the

clamp, means carried by the stop and coacting with the clamp for adjusting the stop relative to the cylinder, a lever connected to the rock shaft, a link pivoted to the lever, and a cam carried by the gripper cylinder 30 to actuate the link.

2. In a sheet gage the combination with a pair of embossing or printing cylinders, grippers carried by one of the cylinders, a rock shaft located over the gripper cylinder, 35 an adjustable clamping sleeve mounted on the rock shaft, a sheet stop depending from the clamp, a set screw mounted on the stop for vertically adjusting the stop, a lever connected to the rock shaft, a link pivoted to 40 the lever, and a cam carried by the gripper cylinder to actuate the link.

In testimony whereof I have hereunto set my hand in the presence of two subscribing witnesses.

WILLIAM B. WAIT.
